A. TRAUBE.

PROCESS OF AND APPARATUS FOR SUPPLYING SOAP.

APPLICATION FILED OCT. 18, 1919.

1,385,735.

Patented July 26, 1921.

Inventor
Abraham Traube
By his Attorney
Mr Wallace White

UNITED STATES PATENT OFFICE.

ABRAHAM TRAUBE, OF BROOKLYN, NEW YORK.

PROCESS OF AND APPARATUS FOR SUPPLYING SOAP.

1,385,735.

Specification of Letters Patent. Patented July 26, 1921.

Application filed October 18, 1919. Serial No. 331,611.

To all whom it may concern:

Be it known that I, ABRAHAM TRAUBE, a citizen of the United States of America, residing at Brooklyn, county of Kings, and State of New York, have invented new and useful Improvements in Processes of and Apparatus for Supplying Soap, of which the following is a specification.

This invention relates to improvements in processes of and apparatus for supplying soap to cleaning machines and the like, the principal object of the invention being to provide a process by means of which the materials containing constituents adapted to form the ingredients of the soap are brought together during their passage to the place of use and chemically combined immediately before entering the machine where the soap is to be used.

10 A further object of the invention is the provision of an apparatus provided with communicating compartments in which the raw materials are separately placed, and means for causing one of such materials to pass in contact with the other and carry along with it only the desired amount of the soap forming ingredient contained in the second material.

20

25

With the foregoing and other objects in view, the invention consists in the novel procedure and combination of parts which will be more fully described hereinafter and particularly pointed out in the claims.

The process forming the main object of this invention consists in placing a material containing potash in the path of a material which is incapable of freeing the potash but containing a constituent which will absorb a certain quantity of the potash, so that upon saturation of the first mentioned material with the second only so much potash will be absorbed by said constituent as is desired to form a cleansing compound or soap.

placed below ground, and for the purpose of removing therefrom any water that may have settled at the bottom a pipe 15 is provided, which extends to the lowermost part 5 of the cone-shaped bottom of the reservoir, and which pipe may communicate with a suitable suction pump (not shown).

In carrying out the present invention with the apparatus above described, a substance, 10 such as caustic soda, preferably in lump form, containing potash as one of the soap-forming ingredients, is placed in the compartment 6, resting on the perforated partition 5, and a material, such as benzene, containing fatty acid as the other soap-forming ingredient, is placed in the reservoir 10. Any suitable means may be applied to the apparatus to cause the material in the reservoir to flow through the pipes 11 and 8 and 15 be thereby sprinkled or sprayed over the material in the compartment 6. In the machine of the prior patent referred to a vacuum creating means is in communication with the tank, and in the apparatus herein 20 illustrated the pipe 16 is intended to establish communication between the tank and a suitable means for creating a vacuum in the tank and thereby causing the flow of the material from the reservoir 10 in the manner above described. By this means only 25 so much of the soap-forming ingredient or potash is carried along into the tank as can be absorbed by the fatty acid in the benzene, so that no free potash, which would 30 be injurious to the articles being cleaned, is introduced into the tank.

From the foregoing it will be seen that in order to vary the amount of cleansing compound or soap to be carried into the tank 40 it will be necessary merely to vary the fatty acid constituent of the benzene, which may be done in a variety of ways that will be obvious to those skilled in the art. The provision of the traps 12 and 7 in the apparatus herein illustrated is to guard against water being carried along with the benzene into the tank, since it is well known that caustic soda is soluble in water and therefore free potash would be carried into the 45 tank if water were permitted to be carried along by the benzene. By the provision of the traps, however, the likelihood of water passing through the compartment 6 and thence into the tank is eliminated, since, 50 water being of greater specific gravity than benzene, any water that may be present in the benzene when it leaves the reservoir will

fall to the bottom of the traps and may be withdrawn from time to time by means of the cocks 13 and 14.

While I have described herein a specific form of apparatus as an illustration of one manner of carrying out my process, it is to be understood that I do not limit my invention to this particular apparatus, since 60 there are numerous ways in which one soap-forming ingredient may be caused to pass in contact with another and in so doing chemically combine to form the desired cleaning compound.

Having thus described my invention, what I claim is:

1. The process of forming a soap solution which consists in conducting a solution of a soap forming acid in a non-aqueous solvent 75 into contact with an alkali while substantially excluding water.

2. The process of forming a soap solution which consists in maintaining a solution of a soap forming ingredient in a non-aqueous 80 solvent in a closed vessel, maintaining another soap forming ingredient in a second closed vessel, and conducting said solution into contact with said second ingredient while substantially excluding water therefrom.

3. The process of forming a soap solution which consists in conducting a solution of fatty acid in a non-aqueous solvent into contact with a mass of alkali in lump form 90 while substantially excluding water therefrom.

4. The process of forming a soap solution which consists in conducting a solution of fatty acid in a non-aqueous solvent into contact with a mass of potash containing substance in lump form, while excluding water therefrom.

5. The process of forming a soap solution which consists in conducting a solution of a soap forming acid in benzene into contact with a mass of potash in lump form, while substantially excluding water therefrom.

6. An apparatus for supplying soap, comprising a container for a solid soap-forming element, a container for a liquid soap-forming element, means for causing the liquid element to pass in contact with the solid element, and a trap in said means for preventing passage of water to said first container.

In testimony whereof I have signed my name to this specification.

ABRAHAM TRAUBE.
